UNITED STATES PATENT OFFICE.

EDWARD H. ANGIER, OF FRAMINGHAM, MASSACHUSETTS.

PACKAGE.

1,395,661.

Specification of Letters Patent.

Patented Nov. 1, 1921.

Application filed December 18, 1916. Serial No. 137,681.

To all whom it may concern:

Be it known that I, EDWARD H. ANGIER, a citizen of the United States, and resident of Framingham, in the county of Middlesex and Commonwealth of Massachusetts, have invented an Improvement in Packages, of which the following description, in connection with the accompanying drawings, is a specification, like characters on the drawings representing like parts.

This invention relates to packages and contemplates particularly a novel manner of packaging toric articles such, for example, as the annular shoes of pneumatic vehicle tires to protect them in storage and shipment. My invention provides a means of covering such articles in a convenient and economical manner with a covering which will protect them from external influences.

My invention may be best understood by reference to the following description of a preferred embodiment of my invention which I have illustrated in the accompanying drawings, wherein—

Figure 1 is a side elevation of a vehicle tire inclosed in a wrapping to form a package;

Fig. 2 is an edge view with parts broken away to show the construction of the wrapper;

Fig. 3 is a central, transverse section through a tire showing an initial stage of the application of the wrapping material thereabout; and

Fig. 4 is a similar view showing the wrapper in its final position.

My invention will most readily be understood by a description of the manner in which the wrapping material is applied about the tire or other article to form a completed package in accordance with my invention. In making this description I shall for the moment disregard the specific nature of the materials which I prefer to utilize and will refer to them after the general structure has been made clear. Referring first, therefore, to Fig. 3 I have there shown a tire shoe 5 and illustrated an intermediate stage in the process of wrapping the same.

In accordance with my invention I provide a suitable strip or sheet of paper 7 which is of a suitable transverse dimension to permit it to encompass the cross-sectional circumference of the annulus which it is intended to cover. The strip 7 may be reinforced if desired by a narrower longitudinal

strip 9 which will assist the user in handling the same and has a further function herein-after to be pointed out. A suitable length of the strip 7 is placed about the circumference of a tire, preferably with its middle portion at the tread thereof as illustrated in Fig. 3, and if desired the ends may be joined. The lateral portions of the strip 7 are then folded inwardly toward the inner circumference of the annulus. It will be understood that since this inner circumference is less than the outer circumference, there will be a fullness of paper which must be disposed of if the wrapping is properly to fit the tire. The fitting is accomplished according to my invention by plaiting or crimping the edges of the strip 7 progressively, as shown at 11 in Figs. 1 and 4, so that the sheet is fitted smoothly about the tread and sides of the tire with the edges in-turned at the beads thereof and presented in opposition to each other. The edges may be joined in any suitable way, but preferably are sealed to provide a sealed package. Preferably this sealing is done in a manner which I will next describe.

Referring again to Fig. 3, preferably, as there shown, before folding the strip 7 inwardly about the tire I apply to the inner circumference thereof a strip 13 of paper, flexible card, or like material, which has its inwardly presented surface gummed. When the edges of the strip 7 are folded inwardly they will overlie this gummed face and may be secured thereto. By proceeding in this manner it is evident that there is no danger of any of the adhesive coming into contact with the tire shoe 5 or other article and injuring the same, or any danger of a portion of the wrapping sticking to the shoe. At the same time the wrapper will be formed into an unbroken, sealed covering about the tire. To further contribute to the security of the closure and to improve the appearance of the package, I preferably cover the edges of the strip 7 which are secured to the inner face of the strip 13 with a second circumferential strip 15 adhesively secured over the same.

While I may use any suitable paper or like material for wrapping, I preferably utilize paper which is reinforced with textile threads or similar strain-resisting filaments, and these threads are desirably disposed in a particular way as regards the several parts of the wrapper. In describing the

preferred construction I will refer more particularly to Fig. 2 which shows an edge view of the tire with parts broken away to show the various reinforcing filaments. Either 5 or both of the strips 7 and 9, and if desired the strips 13 and 15, may be formed of a double thickness of paper secured together by suitable adhesive in which reinforcing filaments are disposed. The strip 7 is herein 10 shown as provided with transverse reinforcing threads 17, that is, threads so disposed that they extend around the cross-section of the tire when the wrapper is in place. The reinforcing tread strip 9 is here shown 15 as reinforced with longitudinal threads which will be disposed circumferentially of the tire when the wrapping is in place. I have also illustrated the strip 15 reinforced with circumferential or longitudinal threads 20 21. The addition of circumferential threads to the central zone of the wrapper, for example, by incorporating them in the strip 9, provides a wear-resisting tread for the tire which considerably increases the durability 25 of the wrapper as a whole. The transverse threads 17 take the strain which is necessarily exerted in fitting the covering about the tire. It is desirable in wrapping a package of this kind to force the beads of 30 the tire somewhat together when the receiving strip is applied. When the compression is released the beads will spread apart again and tension the wrapping to provide a smooth, neat package, and such reinforcing threads as 17 prevent the possibility of a 35 rupture due to such tension. The possibility of conveniently compressing the tire in the package is one of the reasons that renders it desirable to wrap the tire with the seal 40 or joint at the inner circumference as herein described.

It will be noted that the reinforced wrapper herein illustrated and described is simply one example of a wrapper having a central zone reinforced against lengthwise strain and lateral zones reinforced against transverse strain.

From an inspection of Fig. 4, it will be noted that the strip 9 reinforces the covering 45 at the tread which is the point most likely to receive wear. This reinforcing strip 9 might, if desired, be applied to the strip 7

after it is wrapped about the tire, but I find it convenient to attach the strips 7 and 9 together in the first instance, as the strip 7 55 is thereby reinforced so that it may be more readily handled. The strip 9 provides the strip 7 with a central zone comparatively indeformable with respect to the rest of the wrapper. As the central portion of the 60 wrapper which is applied to the tire is little, if any, distorted from its flat shape, this is an advantage since it provides a stout and resistant portion in combination with more flexible lateral zones which may readily be 65 folded over on themselves to form the plaits 11.

I have herein described in great detail a desirable manner of utilizing my invention in wrapping shoes of pneumatic vehicle tires 70 in order that it might be easily understood. It is clear, however, that the features disclosed, while desirable, are not essential to my invention in its broader aspects.

What I do claim and desire to secure by 75 Letters Patent, is:

1. A wrapper for tires or the like of a length to encompass the tire and of a width corresponding substantially to the cross-sectional perimeter of the tire, said wrapper 80 having independent transverse reinforcing filaments and independent longitudinal reinforcing filaments along a central zone thereof.

2. A wrapper for tires or the like of a 85 length to encompass the tire and of a width corresponding substantially to the cross-sectional perimeter of the tire, said wrapper having a central zone reinforced with independent longitudinal filaments and lateral 90 zones reinforced with independent transverse filaments.

3. A wrapper for tires or the like comprising a strip of a length to encompass the tire and of a width substantially corresponding to the cross-sectional perimeter thereof, said strip being reinforced by independent transverse filaments, and a relatively narrow strip secured centrally thereto, said latter strip being reinforced by independent longitudinal filaments.

In testimony whereof, I have signed my name to this specification.

EDWARD H. ANGIER.
